UNITED STATES PATENT OFFICE

ALBERT R. STERN, OF NEW YORK, N. Y.

DESIGN FOR A UNIFORM CAP

Application filed July 30, 1930. Serial No. 36,516. Term of patent 3½ years.

To all whom it may concern:

Be it known that ALBERT R. STERN, a citizen of the United States, and resident of New York city, in the county of Bronx and State of New York, has invented a new, original, and ornamental Design for a Uniform Cap, of which the following is a specification, reference being had to the accompanying drawing, forming part thereof, in which—

Fig. 1, is a side elevational view of a uniform cap, showing my new design, and

Fig. 2, is a front perspective view of said uniform cap.

I claim:

The ornamental design for a uniform cap or similar article as shown.

ALBERT R. STERN.
